CLOTH CUTTING MACHINE

Martin Zawistowski, Huntington, N. Y.

Application February 14, 1935, Serial No. 6,439

7 Claims. (Cl. 164—75)

Cloth cutting machines of the general type shown in my prior Patents 1,378,162 and 1,568,705, usually comprise a supporting base adapted to be advanced along the cutting table and beneath the layers of material to be cut, and a knife having its upper end connected to a power driven crosshead or other suitable member to reciprocate the knife. It is important that the knife be so mounted in respect to the crosshead that its lower end, at the end of the down stroke, will not hit the operating table or the base, as such hitting will cause the machine to jump, will injure the operating table, or will injure or break the knife.

It is frequently necessary to remove the knife to sharpen it or to insert a new one. For that purpose it is desirable that the connection between the knife and the crosshead be such as to permit the slipping of the knife lengthwise through the base in or out of position when the locking screw is loose.

Hitherto, the upper end of the knife has been provided with an open-ended elongated slot for receiving the locking screw or bolt, the slotted part being freely slideable along the screw while said screw was loose. With such a construction there is no assurance that the knife is in any desired relative position with respect to the crosshead when the screw is tightened.

One object of the present invention is to provide a cloth cutting machine in which the locking of the knife cannot be effected unless the blade is in a predetermined position with respect to the crosshead and in which the knife may be slipped lengthwise with respect to the crosshead when the locking member is loose.

Another object is to provide a knife having its upper end so constructed as to insure the attachment of the knife in predetermined position with respect to the crosshead while permitting said knife to be removed by moving it lengthwise with respect to a crosshead and without removing the locking member.

In carrying out my invention, I provide one end of the knife with an open-ended elongated slot extending lengthwise thereof and having means automatically operable upon the tightening or clamping rotation of the locking screw for moving the knife lengthwise into predetermined position with respect to the crosshead. For that purpose, one of the fingers or prongs forming a side of the slot has a series of inwardly extending rack teeth adapted to mesh with a pinion connected to the locking screw. The distance from the crowns of the rack teeth to the inner side

of the adjacent prong is smaller than the maximum diameter of the pinion so that lengthwise movement of the knife cannot be effected without turning the locking screw. The bottom rack tooth is spaced at such a distance from the base 5 of the slot that the pinion when seated in the base of said slot may be rotated without interference from the rack teeth.

In mounting the knife in position it is moved lengthwise until the outer ends of the prongs 10 are underneath the screw head. The screw is then turned in a tightening direction, this movement causing the intermeshing of the pinion with the rack teeth so that the knife is moved inwardly towards the crosshead. This movement 15 continues until the pinion lies in the base of the slot. In this position, the rotation of the screw can be continued until the knife has been clamped to the crosshead.

Since the rack teeth must be on that side of 20 the knife which will permit the movement of the knife towards the crosshead when the screw is turned into tightened position, it is seen that if the knife were reversed, the tightening rotation of the screw would not cause the pinion to 25 mesh with the rack teeth but would tend to eject the knife from the crosshead so that the operator will instantly note that the knife is being mounted in reversed position.

In the accompanying drawing, there is shown 30 for the purpose of illustration, one embodiment of the present invention. In the drawing:

Fig. 1 is a vertical section of part of a cloth cutting machine,

Fig. 2 is a section taken on the line 2—2 of 35

Fig. 1,

Fig. 3 is a section taken on the line 3—3 of Fig. 2, and

Fig. 4 is a side view of one end portion of my 40 improved knife.

The working parts of the machine illustrated are carried by a vertically disposed stand 10 connected at its lower end to a base 11 adapted to advance along a table and underneath the layers of material to be cut as it is guided to follow 45 the pattern or desired line. The upper portions of the machine are not shown but may be of any suitable construction, for instance such as that illustrated in my prior Patents 1,378,162 and 1,568,705. In these prior constructions, there is 50 provided a guiding handle 12 and a rotary electric motor.

The motor is provided with a crank disc connected to one end of a pitman or connecting rod 55 13, the other end being pivotally connected to a

crosshead 14 which is vertically slidable in guides 15 formed in the frame structure of the machine. This crosshead is shown as having substantially V-shaped opposite edges engaging and slidable 5 along corresponding V-shaped guideways in the guides 15. Connected to the crosshead is a reciprocatory knife 16 which is vertically movable in a slot or groove in the front edge of the standard 10. In front of this knife 16 is a vertically 10 adjustable member 17 having at its lower end a presser foot 18, this pressed foot having fingers 20 engaging opposite sides of the knife and serving as a knife guard. The base 11 may have a throat plate 21 presenting a narrow slit 22 onto 15 which the lower end of the knife may enter at the end of its down stroke. The crosshead 14 has an extension 24 and a groove 25 to permit the attachment of the knife 16 to the inner side of the extension 24 and to receive the upper end of the 20 knife. The upper end of the knife 16 is provided with an open-ended elongated slot 26 extending lengthwise thereof and forming a pair of prongs or fingers 27 and 28.

As an important feature of the present invention, the knife 16 is so constructed as to permit the locking of the knife to the crosshead 14 only when the knife is in a predetermined position with respect thereto.

As shown, the prong 27 is formed with a plurality of inwardly extending teeth 30 so as to form a rack bar. For locking the plate in position there is provided a locking screw or stud 31 having a head 32 adapted to receive a suitable turning tool. Adjacent to the inner side of the head 32 is a pinion 33 and beyond said pinion is a reduced threaded extension 34 adapted to be threaded into a hole 35 in the crosshead 14.

The distance between the crowns of the teeth 30 and the facing edge of the prong 28 is smaller 40 than the maximum diameter of the pinion 33, but is sufficiently wide so that upon turning the locking screw 31 in a clockwise direction for a right-hand screw (as viewed in Fig. 3), the teeth of the pinion 33 will mesh with the teeth 30 of the prong 27 and will cause the lengthwise movement of the knife towards the crosshead until the pinion lies in the base of the slot 26.

The base of the slot 26 may have a curvature corresponding to the crown circle of the pinion 50 33 and the bottom rack tooth 30 is sufficiently spaced above the base of the slot 26 so that the pinion 33, when in its lowermost position in the slot, will be free to rotate therein without interference from the teeth 30 as shown in Fig. 3. The hole 35 has a threaded portion to receive the stud 34 and its inner side has a socket to receive the pinion 33 when the screw 31 is in clamping position.

The stud 31 is advantageously enlarged at the 60 extremity of the threaded portion to prevent the stud from being unscrewed too far from the crosshead. For that purpose, a washer 36 may be welded to the end of the threaded extension 34. This washer or other enlargement serves not only to limit the extent of unscrewing of the stud so that the pinion 33 will extend between the prongs 27 and 28 in the loose position of the stud, but also serves to prevent the stud from extending to a loose position where it would break the machine if the motor were to be inadvertently started.

In the mounting of the knife in position, the upper ends of the prongs 27 and 28 are placed against the inner face of the crosshead extension 75 24 and slipped underneath the stud head 32 un-

til the upper tooth 30 is in mesh with the teeth of the pinion 33. A suitable turning tool is applied to the stud head 32, the rotation of which causes the lengthwise movement of the knife inwardly towards the crosshead 14 until the pinion lies in the base of the slot 26. Further rotation of the stud 31 causes the knife to be clamped between the stud head 32 and the crosshead extension 24. If the stud has a right-hand thread, the teeth 30 must be on the left-hand side as viewed in Fig. 3. If the knife is reversed so that the teeth are on the right-hand side as viewed in Fig. 3, the clockwise turning of the stud 31 would tend to eject the knife away from the crosshead. By means of this construction, not only is the knife 16 locked in a predetermined lengthwise position with respect to the crosshead 14 but the mounting of the knife 16 with the lower cutting edge extending in the right direction, is assured.

In order to permit the knife to be used with other machines which are not provided with pinions for effecting the movement above referred to, the base of the slot may have a recess 37 in which a clamping bolt of a diameter less than 25 the distance between the teeth 30 and the prong 28, may seat.

Having thus described my invention, what I claim as new and desire to secure by Letters Patent is:—

1. A cloth cutting machine including a knife, a crosshead adapted to be reciprocated, and means including a rack and a pinion between said crosshead and the upper end of said knife for moving the knife to, and assuring the locking of the knife in predetermined position with respect to said crosshead.

2. A cloth cutting machine including a crosshead, a reciprocatory knife having an elongated slot extending lengthwise at one end thereof, a screw member in said slot for locking said knife to said crosshead, and means whereby said screw member can lock said knife to said crosshead only when said knife is in a predetermined lengthwise position with respect to said crosshead.

3. A cloth cutting machine including a crosshead, a reciprocatory knife, a screw member, and means for moving said knife lengthwise with respect to said crosshead in response to the tightening rotation of said screw member, said means permitting the clamping of said knife onto said crosshead only when the knife has reached a predetermined lengthwise position with respect to said crosshead.

4. In a cloth cutting machine, a power driven crosshead adapted to be reciprocated, a reciprocatory knife having an elongated slot at one end thereof bounded by a pair of spaced prongs, one of said prongs having a series of rack teeth extending inwardly therefrom, a knife clamping screw member threaded into said crosshead, and a pinion on said screw member adapted to mesh with said rack teeth whereby upon rotation of said screw member said knife will be moved lengthwise until said pinion lies in the base portion of said slot, the bottom tooth being sufficiently spaced from the base of said slot whereby said pinion will be freely rotatable in the base portion of said slot to permit the clamping of the knife in position.

5. A cloth cutting machine including a crosshead adapted to be reciprocated, a reciprocatory knife having a pair of prongs at one end thereof forming an elongated slot extending lengthwise

thereof, one of said slots having a series of inwardly extending rack teeth, a screw member passing through said slot for locking said knife to said crosshead, said screw member having a head, and a pinion at the inner side of said head, said pinion being adapted to mesh with said rack teeth and having a maximum diameter substantially equal to the distance between the bases of said teeth and the opposite side of said slot, the bottom rack tooth being sufficiently spaced from the base of the slot to form an opening in the base portion of said slot sufficiently large to permit the free rotation of said pinion therein.

5. As a new article of manufacture, a reciprocating knife blade for use in a power driven cloth cutting machine, said blade having an elongated slot extending lengthwise thereof at one end and forming a pair of spaced prongs for receiving a

10

15

clamping screw therebetween, one of said prongs having rack teeth along the inner edge therefrom.

7. As a new article of manufacture, a reciprocating knife blade for use in a power driven cloth cutting machine, said blade having an open-ended elongated slot extending lengthwise thereof at one end and forming a pair of spaced prongs for receiving a clamping screw therebetween, one of said prongs having rack teeth extending inwardly therefrom, the bottom tooth 10 being spaced from the base of the slot to form an opening at the base portion of the slot, sufficiently large to permit free rotation of a pinion having a maximum diameter substantially equal to the distance between the bases of said teeth 15 and the opposite side of said slot.
